UNITED STATES PATENT OFFICE.

JOHN HICKMAN HYDE, OF LOUISVILLE, KENTUCKY.

TOY VEHICLE.

1,399,212.

Specification of Letters Patent.

Patented Dec. 6, 1921.

Application filed March 15, 1921. Serial No. 452,455.

To all whom it may concern:

Be it known that I, JOHN H. HYDE, a citizen of the United States, residing at Louisville, in the county of Jefferson and State of Kentucky, have invented a new and useful Toy Vehicle, of which the following is a specification.

This invention relates to a child's vehicle of that type adapted to be pushed by the occupant or to be used as a coaster, one of the objects of the invention being to provide a device of this character having novel means whereby it can be adjusted readily to different heights so as to adapt it for use by children of different sizes.

Another object is to provide improved means whereby the adjustment of the parts can be effected, the structure being simple, durable and efficient.

With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings the preferred form of the invention has been shown.

In said drawings—

Figure 1 is a side elevation of the device.

Fig. 2 is a front elevation of a portion thereof.

Fig. 3 is a bottom plan view.

Fig. 4 is a rear elevation a part being broken away.

Referring to the figures by characters of reference 1 designates the body of the vehicle preferably shaped as shown in Fig. 3 so as to have a broad rear or seat portion 2, a forwardly extending neck 3 and an enlargement or head 4 at the front end. In this head is journaled a sleeve or spool 5 from which extends an upwardly projecting steering post 6 having oppositely extending grips 7 at its upper end. Extending upwardly through the sleeve 5 and into the post 6 is a recess 8 into which projects a stem 9 having a series of transverse openings 10 anyone of which is adapted to receive a bolt 11 extending transversely through the post so as to hold the stem in any position to which it may be adjusted within the recess 8.

Secured to the lower end of the sleeve or spool 5 are spaced hangers 12 each of which has a longitudinal slot 13 and arranged between these hangers is a forked block 14 having opposed grooves 15 in which the hangers 12 are adapted to be seated. A clamping bolt 16 extends transversely through the block 14 and through the slots 13 and by tightening the nut 17 on this bolt the hangers 12 and the block 14 can be bound securely together. The stem 9 is preferably extended upwardly from the block 14 so that the bolts 11 and 16 thus constitute two means for holding the block 14 at a desired distance from the spool or sleeve 5.

Journaled within the forked block 14 is a front or steering wheel 18, the same being designed to rotate upon a transverse shaft 19 the projecting ends of which constitute foot rests as will be obvious.

Secured to the bottom of the seat portion 2 of the body close to the sides thereof are V-shaped hangers 20 the rear arms of which are preferably substantially vertical while the front arms are inclined upwardly and forwardly. A cross strip 21 is supported on these front arms of the hangers and is provided, at each end with offset portions 22 which straddle the said arms of the hangers as shown particularly in Fig. 4. The ends of the strip 21 are extended downwardly to constitute ears 23 and in these ears is journaled an axle 24 which extends in front of the hangers 20 and is supported at its ends by the rear wheels 25. The axle 24 obviously holds the offset portions of the strip 21 in engagement with the front arms of the hangers 20 so that the cross strip is thus held against lateral displacement although permitted to slide along the front portions of the hangers.

Secured to the bottom of the body 1 between the ends thereof is a longitudinally extending holding strip 26 in which is formed a slot 27 having suitably arranged notches 28. Adjustably mounted in the slot 27 is a clamping screw 29 which engages the forward ends of downwardly and rearwardly diverging braces 30 the lower ends of which are mounted on the axle 24 between the lugs 23 and the wheels 25.

It will be apparent that by loosening the bolt 29 the strip 21 can be slid upwardly or downwardly along the front arms of the hangers 20 until brought to a desired posi-

tion whereupon the bolt 29 can be adjusted upwardly into one of the notches and there held by tightening the bolt. Likewise the bolts 11 and 16 can be removed and loosened respectively and the wheel 18 adjusted toward or from the head 4 and subsequently resecured. Thus the vehicle can be adjusted for use by children of different sizes. By arranging the notches 28 in the upper wall 5 of the slot 27 the bolt 29 will tend to bind against the wall of the notch in which it is seated, when the vehicle is subjected to a load, thus insuring against accidental lowering of the rear end of the body while in use.

15 What is claimed is:—

1. A child's vehicle including a body, a front steering wheel adjustably connected thereto, rear hangers on the body having inclined portions, a cross strip straddling and 20 slidable on the inclined portions of the hangers, a wheel supported axle carried by said strip and coöperating with the hangers for holding the strip in engagement with the hangers, and coöperating means upon the 25 axle and body for holding the axle and strip in any position to which they may be adjusted relative to the hangers.

2. A child's vehicle including a body, a front steering wheel adjustably connected 30 thereto, rear hangers on the body having inclined portions, a cross strip slidable on said portions, an axle engaging the cross strip and coöperating with the hangers for hold-

ing the strip in position thereon, supporting wheels engaging the axle, a slotted holding strip secured to the body, a brace 35 extending from the axle, and means extending through the slotted holding strip for adjustably securing the brace to said strip and supporting the axle at a desired position on 40 the hangers.

3. A child's vehicle including a body, a front steering wheel adjustably connected thereto, rear hangers on the body having inclined portions, a cross strip slidable on 45 said portions, an axle engaging the cross strip and coöperating with the hangers for holding the strip in position thereon, supporting wheels engaging the axle, a slotted holding strip secured to the body, braces 50 connected to the axle and extended to opposite sides of the holding strip, and clamping means extended through the braces and the holding strip for securing the braces against movement and holding the axle at a desired 55 position upon the hangers, there being notches in one wall of the slot to receive the clamping means while the body is supporting a load.

In testimony that I claim the foregoing 60 as my own, I have hereto affixed my signature in the presence of two witnesses.

JOHN HICKMAN HYDE.

Witnesses:

STANLEY BIRD,
CHESTER P. KOCH.
